Filed Oct. 11, 1957, Ser. No. 689,574

9 Claims. (Cl. 74—7)

This invention relates to engine starters and more particularly to a starter drive of the inertia type wherein the pinion is automatically propelled into and from engagement with the gear of the engine to be started.

It is an object of the present invention to arrange the parts of a starter drive on a threaded starting motor shaft so the engine to be cranked may be cranked in either direction of rotation.

Another object of the present invention is to arrange the resilient members of an inertia starter drive so a yielding connection is formed when the pinion is moved by the starter motor and a nonyielding connection is formed when the pinion is rotated by the engine. This will prevent rebounding of the pinion gear into engagement with the engine gear after the engine becomes self-operative.

A further object of the present invention is to provide an inertia drive with a torsion return spring and a resilient connection between the pinion gear and its drive which will permit a limited rotation between the pinion gear and its drive when the pinion is moved by the starting motor and a nonyielding connection is formed when the pinion is rotated by the engine. This will aid the pinion in demeshing from the engine gear and will prevent the pinion from rebounding into the engine gear after the engine becomes self-operative.

Another object of the present invention is to provide the starting motor shaft with a thread portion and a smooth surface portion and to support a sleeve which axially moves on the thread portion, on the smooth surface portion with a nylon bearing so the pinion which rides upon the sleeve will be supported when it is in mesh with a gear of the engine to be started.

Another object of the present invention is to provide a shoulder between a reduced portion of the shaft and the remainder of the shaft which shoulder will act as a stop to limit the movement of a sleeve which is threadedly connected to the reduced portion of the shaft.

A further object of the present invention is to provide an inertia starter drive with a minimum number of parts which will decrease the cost of manufacture of the drive and provide a drive that is reliable in its operation. This is accomplished by using a threaded starter shaft and a torsion spring to aid in the demeshing of the pinion gear.

Further objects and advantages of the present invention will be apparent from the following description, reference being had to the accompanying drawings wherein preferred embodiments of the present invention are clearly shown.

In the drawings:

Figure 1 is a cross-sectional view of a pair of starter drives according to the present invention which are arranged on opposite sides of a gear that is connected to the engine to be started.

Figure 2 is a view of the drive parts in Figure 1 wherein one of the drives is in meshing engagement with the engine gear.

2

Figure 3 is a view taken along line 3—3 in Figure 1. Figure 4 is a cross-sectional view of a single starter drive showing a modification of the drive in Figure 1. Figure 5 is a view taken along line 5—5 in Figure 4.

In the embodiment shown in Figures 1 and 2 of the drawings, the shaft 20 is adapted to be rotated in either direction by a conventional type starting motor, not shown. The shaft 20 has a reduced diameter portion 22 which is separated from the main portion 24 of the shaft by the shoulder 26. The reduced portion of the shaft is provided with threaded portions 28 and 30 which are separated from each other by a smooth surface portion 32. The threaded portions 28 and 30 in the embodiment shown are preferably formed in the material of the shaft 20. This arrangement will provide a certain economy in manufacture and will reduce the over-all size of the remaining parts of the starting drive. The threaded portions 28 and 30 are located on opposite sides of a gear 34 which is connected to the engine to be started which is not shown. In conventional practice, the gear 34 would be connected to the flywheel and designated as a ring gear. The shaft 20 may also be grooved as at 36 and 38 to receive C-shaped metal rings 40 and 42. The ring 40 will be pressed against the shoulder 26 and will prevent damage thereto when the shoulder acts as a stop. The ring 42 is of a hardened metal type and will act as a stop in itself. The shaft is also provided with grooves which receive the C-shaped snap rings 44 and 46 arranged to position one of the ends of the torsion springs 48 and 49 respectively as shown. The function of these springs will become hereinafter apparent.

The drive assembly shown in Figure 1 includes two drives 50 and 52 which are identical and located on the opposite sides of the ring gear 34. For the purpose of explanation, the parts of the drive 50 will be described. It is to be understood that like numerals and functions of the parts to which the numbered parts relate will apply to the parts of the drive 52. The drive 50 includes the coupling 54, the pinion gear 56, the shell 58, the resilient members 60 and the snap ring 64 which is received in the internal groove 66 in the shell 58 to hold the parts of the drive 50 assembled.

The coupling 54 formed as shown has a central hub 68 that is internally threaded to threadedly engage the threaded portion 28. The outwardly extending flange 70 on hub 68 is provided with a slot 72 to receive the other end of the torsion spring 48 which has its convolutions surrounding the shaft 20 when the drive 50 is in the normal or at rest position. Extending from the flange toward the pinion gear 56 are lugs 74. The drive 50 in Figure 1 has four spaced lugs 74. These lugs are designated as lugs 74A and 74B and extend substantially radially from the hub 68 and are spaced as shown in Figure 3. The lugs 74A and 74B in the embodiment shown are provided by the extending arms of a pair of U-shaped parts 76 which have their central portions secured as by welding to the flange 70.

The shell 58 is generally cup-shaped to have a bottom wall 78, a central opening 80 in the bottom wall 78 and the internal groove 66 which is formed on the side wall 82. The material of the side wall 82 on diametrically opposite sides thereof and adjacent the bottom wall 78 is struck in to provide a pair of inwardly extending lugs 84 which extend substantially radially inwardly as in Figure 3. When the parts of the drive 50 are assembled, the lugs 84 each will have one surface in engagement with one of the lugs 74A. Thus, one surface of lugs 84 will be in metal to metal contact with the lugs 74A. Positioned between the other surface of lugs 84 and the lugs 74B are the resilient members 60.

The pinion gear 56 is preferably secured directly to the bottom wall 78 as by welding or brazing and has a

central bore 86 sized to slide on the sleeve bearing 87 which is positioned on smooth surface portion 32 of shaft 20 and which is formed of nylon material or any other suitable bearing material. This bearing may be molded in place on the shaft or may be fitted thereto by any other well known mechanical expedients. The teeth of the pinion are formed with the conventional chamfers to aid in the meshing and demeshing with the ring gear 34.

The resilient members 60 are shaped as shown in Figs. 2 and 3. These members 60 are formed of rubber-like or elastomeric materials. The particular materials from which members 60 may be formed are well known and may consist of natural or synthetic rubber or other suitable plastics or combinations thereof which are compounded and cured to provide the proper degree of resiliency. The members 60 are arcuate in shape and have flat end walls arranged to engage the lugs 84 and 74B. The inner surface 88 is curved to engage a portion of the cylindrical outer surface of hub 68. The outer surface 90 is also curved and is maintained normally spaced from the complementary cylindrical surface provided by the inner surface of side wall 82. The spacing between the outer surface 90 and the inner surface of wall 82 is maintained by the lugs or bulbous portions 92 which extend outwardly from the surface 90. The parallel end walls 94 have the spaced extending ribs 96 thereon. The ribs 96 are maintained constantly in engagement with the flange 70 and the bottom wall 78 as in Figure 1 and are deformable to permit a slight axial movement between the hub 68 and shell 58.

When the shaft 20 is rotated in the direction of arrow 98 in Figure 3, the drive 50, because of its inertia will not rotate, but will move axially on the threaded portion 28 to the right to the position shown in Figure 2. When the pinion is completely moved to the right, it will be in mesh with the ring gear 34 and the convolutions of the spring 48 will be tightened about shaft 20. The shock which accompanies the sudden stops of the pinion gear as it is moved into the full mesh position is absorbed by the resilient members 60 of drive 52. After the pinion 56 is in mesh with the ring gear 34, the continued rotation of the shaft 20 will rotate the hub 68. The rotation of the hub 68 will be transmitted through lugs 74B against the resilient members 60 to circumferentially compress the members 60 against lugs 84. When the resilient members are thus circumferentially compressed, the surface 90 will move radially outwardly to at least partly fill the space between the surface 90 and the inner cylindrical surface of the side walls 82. Thus, a resilient connection is formed between the lugs 74B and 84 when the pinion gear 56 is driving the ring gear 34. In event tooth end abutment occurs between the pinion gear 56 and the ring gear 34 when the pinion gear 56 is being moved forward into meshing position with the ring gear 34, the resilient members 60 will be slightly axially and circumferentially compressed before the pinion gear 56 rotationally responds to the rotation of shaft 20. This compression of the resilient members 60 will aid the pinion in moving from its tooth end abutting position into full meshing position.

After the axial movement to the right of pinion gear 56 stops, the pinion will respond to the rotation of shaft 20 and rotate gear 34. When the engine becomes self-operative, ring gear 34 accelerates and will tend to have a greater rotational speed than pinion gear 56 and shaft 20. This relative rotation will cause the drive 50 to be rotated on thread portion 28 and move to the left from the position in Figure 2 so the pinion gear 56 will move from its meshing engagement with the ring gear. The spring 48, which was previously stressed when the pinion gear 56 moved into the meshing position will aid the movement of the pinion gear 56 to the left. During this period, a relatively nonresilient driving connection will be formed between the pinion gear 56 and the hub 68.

This nonresilient connection is the result of the metal to metal contact between lugs 74A and lugs 84 and will impart a positive nonresilient rotative impulse to the hub to eliminate the back lash or kickback which occurs when the pinion is connected to the hub by a connection that is resilient in both directions of rotation. We have determined that a nonresilient connection, as described, between the pinion gear 56 and hub 68, will eliminate the rebounding of the pinion gear into the ring gear after the engine becomes self-operative.

The threads of both threaded portions 28 and 30 are left-handed. Therefore, when the shaft 20 rotates clockwise as viewed in Figure 3, the drive 50 will advance from left to right and drive 52 will be pressed against the ring 42. In this connection, it is noted that the torsion springs 48 which normally loosely surround the shaft 20 will normally maintain the drives against the rings 40 and 42 when the shaft 20 is not rotating. When the shaft is rotated to move one of the drives toward the gear 34, the spring associated with the moving drive will become extended and its convolutions decreased in diameter. The springs will thus aid the pinion gear drive in demeshing from the ring gear after the engine becomes self-operative. When the shaft 20 is rotated in a clockwise direction, the drive 52 will advance from right to left as shown in Figure 1. The parts of this drive 52 will function in the same manner as the corresponding parts described for drive 50. It is clearly apparent that the above arrangement will cause the engine to be cranked in either direction of rotation depending on the direction of rotation of shaft 20.

In the embodiment shown in Figures 4 and 5 of the drawings, the shaft 120 is arranged to be driven in one direction of rotation only, indicated by the arrow in Figure 5, by a starting motor, not shown. The drive 122 includes a sleeve 124 which is internally threaded to engage the threaded portion 126 of the shaft 120. A flanged member 128 secured to sleeve 124 has lugs 130 which radially extend from the opposite sides of sleeve 124 and extend longitudinally along the outer surface of the sleeve toward the pinion gear 132 in a plane parallel with the axis of the shaft 120. The purpose of these lugs 130 will become hereinafter apparent. The pinion gear 132 is axially and rotatably movable on the outer surface of the sleeve 124. This pinion gear has a coupling member 134 secured thereto which has a pair of lugs 136 thereon which extend radially on opposite sides of the sleeve 124 in a plane parallel with the axis of the shaft 20. The flange 128 and coupling member 134 are disposed relative to each other so the lugs 136 and 130 will be in the arrangement shown in Figure 5. That is, one surface of each of the lugs will be in engagement with a resilient member 138 while the other surface will be metal to metal contact with an adjacent metal lug. Secured to the outer surface of coupling 134 is a shell 140. This shell 140 will have its free end riding upon the flange 128 and will completely enclose the lugs 136 and 130 and will provide enclosed areas or chambers 142 between the shell 140, the outer surface of the sleeve 124 and the adjacent surfaces of the lugs 136 and 130.

Positioned within each of the chambers 142 are resilient members 138. Each of these members 138 is formed of a suitable elastomeric compound such as the well-known natural or synthetic rubbers, a suitable organic plastic or mixtures thereof which are compounded to provide the proper resilient characteristics thereto. The members 138 are sized to not completely fill the spaces 142. The members 138 have provided lugs or bulbous portions 144 thereon. These lugs 144 are arranged to engage the outer shell 140 to provide an open space 146 between the outer surface of members 138 and the inner surface of the shell 140. This space 146 will permit the rubber material forming members 138 to move radially outwardly when abutment 136 is rotated relative to abutment 130. It is well known that rubber is virtually un-

compressible. This space will permit the rubber to provide the yielding restraint to oppose the movement between the abutments 136 and 130. The members 138 are also provided with ribs or ridges 147 which have their apexes in constant engagement with the members 128 and 134. These apexes of ribs 147 are arranged to provide an increased resistance to movement proportional to the distance moved when the coupling 134 and flange 128 are moved toward each other.

The shaft 120 is also provided with a stop portion 148 which is engaged by sleeve 124. The drive parts are held assembled on sleeve 124 by the snap ring 149 which is arranged to permit the pinion gear 132 to move axially on sleeve 124 toward flange 128. A conventional fixed stop means 150 on the free end of shaft 120 will limit the axial movement of the drive to the right. In this embodiment the torsional spring 48 as used in the embodiment shown in Figure 1 is replaced by a compression spring 152.

The parts of the starter drive will have a similar operation during meshing and demeshing operation with the ring gear 154 as described in the embodiment shown in Figure 1.

While the embodiments of the present invention as herein disclosed constitute preferred forms, it is to be understood that other forms might be adopted.

What is claimed is as follows:

1. In an inertia type starting motor drive, comprising: a nut having a threaded engagement with a threaded portion on a starting motor shaft, outwardly extending lugs on the nut, a pinion gear slidable and rotatable over a smooth portion of the shaft, a shell connected to the pinion, and inwardly turned lugs integral with and extending from the shell interposed between the lugs on the nut and in metal to metal contact therewith, said lugs forming a direct drive between said nut and pinion.

2. In an inertia type starter drive, the combination comprising: a nut having a threaded engagement with a threaded portion on a starting motor shaft, outwardly extending lugs on the nut, a pinion gear slidable and rotatable over a smooth portion of the shaft, a shell connected to the pinion, an integral inwardly turned lug on the shell having a surface in contact with a lug on the nut and a resilient means disposed between the lugs on the nut and on the shell urging the lug on the shell into surface contact with the lug on the nut, said resilient means forming a resilient drive in one direction of movement of said pinion and said lugs forming a direct drive in an opposite direction of movement of said pinion.

3. In an engine starting apparatus, the combination comprising: a rotatable shaft, a threaded portion on the shaft, a sleeve having an outer smooth surface threaded on the threaded portion and axially movable on said shaft when said shaft is rotated, spaced lugs on the sleeve, a pinion gear freely movable axially and rotatively on said sleeve, spaced lugs connected to said pinion interposed between and in contact with the lugs on the sleeve, a shell connected to the pinion and enclosing said lugs to provide a confined space between adjacent interposed lugs on the sleeve and pinion, and a resilient means in the space between the adjacent lugs to provide a resilient connection between the pinion and sleeve in one direction of rotation only.

4. In an engine starting apparatus, the combination comprising: a rotatable shaft, a threaded portion on the shaft, a sleeve having an outer smooth surface threaded on the threaded portion and axially movable on the shaft when the shaft is rotated, a pinion gear freely movable axially and rotatively on the sleeve, a flange on the sleeve, spaced abutments extending from the flange longitudinally

along the outer surface of the sleeve toward said pinion, spaced abutments connected to the pinion extending toward the flange and interposed between the abutments on the flange, a shell connected with the pinion and enclosing said abutments to provide a plurality of confined spaces between the adjacent interposed abutments on the pinion and flange, and a resilient means yieldably resisting longitudinal movement of the pinion on said sleeve and sized to permit a limited free rotary movement of the pinion on the sleeve in one direction of rotation only.

5. In a starting apparatus for an engine, the combination comprising: a rotatable shaft, a nut threadedly connected with said shaft and adapted to be moved axially on said shaft a predetermined distance in response to relative rotation between the sleeve and shaft, a pinion gear freely movable on said shaft and movable into mesh with a gear connected with the engine to be started, a means resiliently connecting the pinion and nut and a torsion spring connected between the shaft and nut for aiding the movement of the pinion from its meshing engagement with the gear after the engine becomes self-operative.

6. In a starting apparatus for an engine, the combination comprising: a rotatable shaft, a nut threadedly connected with the shaft and adapted to move axially on said shaft in response to relative rotation between the shaft and nut, a pinion freely movable on the shaft and movable into meshing engagement with a gear connected with the engine to be cranked, a torsion spring surrounding said shaft and connected with the nut and shaft for yieldably opposing movement of the pinion on the shaft and means connecting the pinion and nut.

7. In a starting apparatus for an engine, the combination comprising: a rotatable shaft, a reduced portion on said shaft having a shoulder separating the reduced portion of the shaft from the remainder of the shaft, a washer engaging said shoulder, a threaded portion on said reduced portion adjacent the shoulder, a smooth surface on said reduced portion, a nut having internal threads engageable with the threaded portion and the smooth surface portion, said nut being axially movable on the reduced portion of the shaft in response to relative rotation between the shaft and nut.

8. The combination as set forth in claim 4 wherein the resilient means consists of rubber-like members having oppositely extending ridges in engagement with the flange and pinion which are adapted to compress and yieldably maintain pinion and sleeve axially in position.

9. In a starting apparatus for an engine, the combination comprising: a rotatable shaft, a reduced portion on said shaft forming a shoulder separating the reduced portion of the shaft from the remainder of the shaft, a threaded portion on said reduced portion located adjacent the shoulder, a nut having internal threads engageable with the threaded portion, a pinion rotatable and slidably on said shaft and driven by said nut, resilient means disposed between said pinion and nut for taking up axial shock therebetween, and a torsion spring having one end thereof connected to and engaging said shaft and having an opposite end connected with said nut for urging said nut toward said shoulder.
